**METHOD OF FLAKING WOOD AND ROTARY
TUNNEL FLAKER THEREFOR**

Richard D. Kiser, Longview, Wash., assignor of one-half
to Dale L. Schubert, and one-half to Industrial De-
velopment Co. Inc., Tacoma, Wash., a corporation of
Washington

Filed Apr. 6, 1959, Ser. No. 804,205

6 Claims. (Cl. 144—230)

This invention relates to a method of flaking wood and to a rotary tunnel flaker therefor.

In the manufacture of wood flakeboard, wood logs or billets first are reduced to flakes by cutting them across the grain. The flakes then are mixed with a thermosetting resin and size, formed into a felt and consolidated into the desired thickness and density in a hot press.

In the foregoing sequence, it is important to provide wood flakers which will operate rapidly, smoothly, and efficiently so as to produce a large volume of flakes at minimum cost and at maximum production rate. In addition, it is essential that the flakes produced be of substantially uniform thickness, have reasonably sharply defined side edges, and be free from sticks and slivers. Any substantial irregularity in flake dimensions obviously will be reflected in a corresponding irregularity in the properties of the finished board.

This problem is particularly acute in view of the fact that in the usual flaker the flakes pass as they are formed to gullets located ahead of the knife. This requires making a reverse bend around a sharp corner which, in turn, induces breakage of the flakes.

Accordingly it is the general object of the present invention to provide a rotary, cross-grain, wood flaker which will produce uniform flakes at a high production rate even when the wood being processed is frangible and easily broken, as in the case of cedar.

It is another important object of the present invention to provide a flaker of the indicated class which is capable of precision cutting over long operating periods, but which is easily disassembled and assembled as necessary for servicing and knife sharpening.

In the drawings:

FIG. 1 is a fragmentary plan view of the herein described flaker;

FIG. 2 is a fragmentary sectional view taken along line 2—2 of FIG. 1; and

FIGS. 3 and 4 are exploded perspective views of the upper and lower cutter knife assemblies, respectively, in the rotor of FIGS. 1 and 2.

Generally stated, the herein-described method of flaking wood comprises severing flakes from a piece of wood with a knife, and guiding the flakes across the leading face of the knife and around the base thereof to a discharge station behind the knife, thereby avoiding reverse curling of the flakes and minimizing breakage thereof.

The apparatus by which the foregoing method is accomplished broadly comprises a rotor, a knife mounted on the rotor, a gib means securing the knife in cutting position, and a passageway through the rotor positioned and dimensioned to pass a flake cut by the knife along the leading face and around the base thereof to a discharge station behind the same.

Considering the foregoing in greater detail and with particular reference to the drawings:

The flaker of our invention comprises a forged steel, cylindrical rotor 10 provided with shaft 12. The rotor may be of substantial size, for example, from 2 to 3 feet long and from 18 to 36 inches in diameter.

A plurality of circumferentially spaced, parallel, longitudinal gibways 14, which preferably are wedge-shaped in

2

section, are planed out of the rotor. They communicate with knifeways 16 which, in the embodiment illustrated, extend inwardly beyond the gibways and may be formed in the same operation.

5 Deep pockets or gullets 18 having a pronounced radius are milled out of the rotor periphery at longitudinally spaced intervals along each knifeway, intercepting the knifeway and gibway.

Wedge-shaped gibs 20, preferably formed in short sections for ease of handling but shown for simplicity in FIGS. 3 and 4 as extending the full length of the rotor, are seated in each of the gibways. The gibs are formed at spaced intervals with transverse, cutaway portions or passageways 22. These register with gullets 18. Also, 15 the gibs are drilled and tapped at intervals to receive screws 24 bearing against the bottoms of the gibways in the manner indicated in FIG. 2.

Filling or insert blocks 26 may be provided opposite the gib sections receiving the screws to provide continuity of rotor surface. Cutaway portions in the blocks register with the cutaway portions in the gibs to provide continuity of passageways 22 inwardly from the rotor surface.

Knives 30 are seated in knifeways 16. Each knife 25 may comprise a flat bar substantially co-dimensional with the gib. Its outer surface is formed with projecting knife edge sections 32 alternating with recessed, non-cutting sections 34. The base is cut away at spaced intervals registering with the spaced gullets 18 with a radius as 30 indicated at 36 to provide a smooth, continuous passageway for flakes from the front leading side of the knife inwardly along passageway 22 and around the radius 36 to the gullet on the trailing side of the knife.

In assembling the flaker the gibs and knives are inserted 35 in the gibways and knifeways, respectively, spanning the gullets 18, and the desired knife adjustment secured. Screws 24 then are tightened down, thus drawing the gibs and insert blocks outwardly and wedging the knives in position.

40 Wood is fed to the rotor across a bedplate, not illustrated, and preferably in a crossgrain direction. The staggered cutting sections of the knives thereupon cut flakes which are guided inwardly along passageways 22 ahead of the knives and across their front faces, thence 45 around the passageways forced in part by cutaway portions 36 at the bases of the knives, and into gullets 18 on the trailing side of the knives. This movement of the flakes is afforded because they are much thinner than the passageways (FIG. 2). They are stored there pending 50 centrifugal discharge from the apparatus upon continued rotation of the rotor.

In this manner the flakes are cleanly severed from the 55 woody matrix and preserved with a minimum of breakage. As a result, a uniform flake product is produced which may be used to great advantage in the production of flakeboard of uniform properties.

It is to be understood that the form of our invention herein shown and described is to be taken as a preferred 60 example of the same and that various changes in the shape, size and arrangement of parts may be resorted to without departing from the spirit of our invention or the scope of the subjoined claims.

Having thus described my invention, I claim:

1. The method of flaking wood which comprises severing flakes from a piece of wood with a rotary knife, and guiding the flakes across the leading face of the knife and around the base thereof to a discharge station behind the knife, thereby avoiding reverse curling of the flakes and minimizing fracturing the same.

2. The method of flaking wood which comprises cross-cutting a piece of wood with a rotary knife having a knife edge and a base, the knife edge being maintained substan-

tially parallel to the wood grain, thereby severing cross-cut flakes from the wood, and guiding the flakes across the leading face of the knife and around the base thereof to a discharge station behind the knife, thereby avoiding reverse curling of the flakes and minimizing the fracturing thereof in a direction along the grain.

3. A rotary flaker comprising a rotor, a knife having a knife edge and a base mounted on the rotor, and gib means securing the knife in cutting position, the rotor being provided with a passageway therethrough positioned and dimensioned to pass a flake cut by the knife along the leading face and around the base thereof to a discharge station behind the knife.

4. A rotary flaker comprising a rotor having in its peripheral surface a plurality of spaced, parallel, longitudinal, intercommunicating gibways and knifeways, a plurality of gib-knife assemblies seated one in each of the gibways and knifeways and each comprising a gib dimensioned to seat in the gibway ahead of the knife and provided with spaced transverse passageways, a knife having 15 projecting cutting sections alternating with recessed non-cutting sections seated in the knifeway with the cutting sections aligned with and opposite the passageways which accordingly lead across the front face of the knife and around the base thereof, gullet means in the rotor behind the knife communicating with the passageways in the gib, and means for securing the gib-knife assembly in the rotor.

5. The flaker of claim 4 wherein a continuous gullet is provided through the trailing portion of the gib, around the base of the knife and through the rotor behind the

knife, thereby providing a way for passage of the flakes along the leading face and around the base of the knife.

6. A rotary flaker comprising a rotor, and a knife mounted on the rotor and having a knife edge and a base, the rotor being provided with an inwardly extending gullet which is traversed by the knife to provide a passageway which extends continuously from the rotor surface inward along the leading face of the blade and thence around the base of the blade to the rotor surface 10 on the trailing side of the blade.
